United States Patent C

Patented Sept. 20, 1966

205,812

DEEP SUBMERGENCE RESEARCH SUBMARINE

Herman G. Ulbrich, Los Altos, Calif., assignor to Lockheed Aircraft Corporation, Burbank, Calif.

Filed Dec. 20, 1965, Ser. No. 238

Term of patent 14 years

(Cl. D71—1)

FIG. 1

FIG. 2

FIG. 3

FIG. 4

FIGURE 1 is a perspective view of the deep submergence research submarine showing my new design;

FIGURE 2 is a rear or stern view of the inventive design;

FIGURE 3 is a side elevational view of the invention, and

FIGURE 4 is a top or plan view of the submarine.

I claim:

The ornamental design for a deep submergence research submarine, as shown.
